SURFACTANT MIXTURES

George L. Broussalian, Overland, Mo., assignor to
Monsanto Company, a corporation of Delaware
No Drawing. Filed Oct. 8, 1963, Ser. No. 314,648
9 Claims. (Cl. 252—152)

The present invention relates to mixtures of surface active agents having surprisingly effective general surface active properties. More particularly, this invention relates to novel mixtures containing certain (a) vicinal acylamido higher alkyl sulfonates, (b) beta-ethylenically unsaturated higher alkene sulfonates, and (c) beta-monohydroxy higher alkyl sulfonates, which mixtures are synergistically effective with respect to at least several of their important surface active properties.

Vicinal acylamido higher alkyl sulfonates such as those having the structure illustrated by Formula 1:

(I)

wherein R and R' are either hydrogen or alkyl radicals and the total (combined) number of carbon atoms in R plus R' is from about 8 to about 22, R'' is an alkyl radical containing at most about 6 carbon atoms and M is either an ammonium, alkali metal, or alkaline earth metal cation; are excellent general purpose surfactants as well as excellent lime soap dispersants. One of the preferred processes for manufacturing such valuable vicinal acylamido higher alkyl sulfonates involves the controlled interreaction of an appropriate olefin with sulfur trioxide to form, initially, a beta sultone, in accordance with Equation I:

(I)

The beta sultone can then be reacted with an appropriate nitrile to yield a 2-dioxy-1,2,5-oxathiazine which in turn can be hydrolyzed and then "neutralized" with an aqueous base to form the desired sulfonate:

(II)

(III)

One significant problem encountered by those who intend to manufacture the vicinal acylamido higher alkyl sulfonate materials via such olefin-SO₃-nitrile processes relates to the fact that, invariably in these processes, a significant amount of by-product beta-hydroxy higher alkyl sulfonate material is also formed. These beta-hydroxy higher alkyl sulfonates have structures such as those illustrated by Formula 2:

2)

Depending upon the actual conditions experienced in conducting the above-described process, the amount of

2

such by-product beta-hydroxy sulfonate material often ranges from about 2 to 5 weight percent to about 50 weight percent, or even more, based on the weight of vicinal acylamido higher alkyl sulfonate produced in the

5 same process. This beta-hydroxy sulfonate material is generally a very poor surfactant. Consequently, in order to optimize the surfactant properties of their preferred vicinal acylamido higher alkyl sulfonate products, potential manufacturers of vicinal acylamido higher alkyl sulfonates who intend to utilize such olefin-SO₃-nitrile processes (particularly when they use process conditions that result in the formation of, for example, at least about 10 weight percent of the by-product beta-hydroxy sulfonate material) would have to either (a) remove a large 10 proportion of the beta-hydroxy sulfonate material from the process mixture (i.e., purify the vicinal acylamido alkyl sulfonate) or (b) somehow enhance the surfactant properties of the process mixture (of vicinal acylamido higher alkyl sulfonate with beta-hydroxy higher alkyl sulfonate). From the standpoint of economics, this 15 latter approach would be preferred, provided an inexpensive procedure could be made available in which the surfactant properties of such mixtures can be enhanced. The "detracting" effect by the beta-hydroxy sulfonate material on the generally excellent surfactant properties of the vicinal acylamido sulfonates can be appreciated from the fact, for example, that in a given standard test for detergency in which cotton fabrics are washed under controlled conditions in an aqueous solution containing 20 a given concentration of the surfactant material, the use of a mixture consisting of about 80 weight percent of sodium 2-acetamido-1-hexadecyl sulfonate and about 20 weight percent of sodium 2-hydroxy-1-hexadecyl sulfonate resulted in a cleaning or detergency value of only 25 95, while pure sodium acetamido-1-hexadecyl sulfonate gave a detergency value of 110.

It is an object of the present invention to provide surfactant compositions containing at least one of the above-described vicinal acylamido higher alkyl sulfonates plus 30 an amount of one of the above-described beta-hydroxy higher alkyl sulfonates which would ordinarily be sufficient to detract from the surfactant properties of the vicinal acylamido sulfonate material (practically any amount of the beta-hydroxy material detracts to at least 35 some extent) and a third surfactant material, the presence of which overcomes the detracting effect of the beta-hydroxy sulfonate material on the surfactant properties of the composition.

The above, as well as other objects of this invention, 40 can be accomplished by incorporating into the mixture (of vicinal acylamido and beta-hydroxy sulfonates) an effective amount of a beta-ethylenically unsaturated higher alkene sulfonate such as one of those illustrated 45 by Formula 3:

(3)

50 wherein M has the same meaning as in Formula 1, above, and the significance of R'' and R^{IV} will be described below. Although, in some instances the use of as little as about 5 weight percent (or even less) of the unsaturated material (based on the total combined weight of the acylamido and hydroxy sulfonates) in the mixture can overcome the detracting effect of the beta-hydroxy sulfonate, generally at least about half as much beta-unsaturated material as the amount of beta-hydroxy material in the mixture should be utilized therein. When 55 at least this amount is utilized, particularly when amounts of beta-hydroxy material up to about 20 weight percent, based on the total combined weight of vicinal acylamido

sulfonate and beta-hydroxy sulfonate material, are present in the surfactant mixtures, the beneficial synergistic properties of the resulting mixture are most evident; the general surfactant properties of the resulting mixture being surprisingly better than those of any of the individual components of the resulting mixture alone. However, the beneficial effect of the beta unsaturated material can generally be noted when as little as about 20 weight percent (based on the weight of beta-hydroxy sulfonate material in the mixture), and sometimes even smaller amounts, of the beta unsaturated material is present therein; particularly in mixtures containing larger amounts of the beta-hydroxy material. It is preferred, however, that the beta unsaturated material be present in the surfactant mixtures of the present invention in amounts at least equal to those of the beta-hydroxy material therein. Stated otherwise, the surfactant mixtures of this invention generally contain from about 40 to about 98 (preferably from about 50 to about 90) weight percent of one or more vicinal acylamido sulfonates; from about 1 to about 30 (and more usually from about 5 to about 20) weight percent of one or more of the detrimental beta-hydroxy sulfonates described above; and from about 0.5 to about 30 (preferably from about 5 to about 20) weight percent of one or more of the above-described beta-ethylenically unsaturated sulfonates. These weight percentages are based only upon the combined weight of these three types of sulfonates in the surfactant mixtures. It will be understood that these three sulfonates are not necessarily the only components in the surfactant mixtures of the present invention.

In the novel surfactant mixtures of the present invention, generally the vicinal acylamido sulfonates will be present in greater amounts than either of the other classes or types of surfactants. Thus, the weight ratio of the vicinal acylamido sulfonates to beta-monohydroxy higher alkyl sulfonates, respectively, in these surfactant mixtures can be from about 20 or more to 1, to about 2:1, and is generally from about 15:1 to about 4:1, while the weight ratio of the vicinal acylamido sulfonates to beta-ethylenically unsaturated higher alkene sulfonates, respectively, therein is generally from about 40 or more to 1, to about 5:1, and is preferably from about 15:1 to about 4:1.

As it was stated hereinbefore, the vicinal acylamido sulfonate materials that have been found to be useful in the practice of the present invention are those having the formula

wherein R and R' are either hydrogen or alkyl radicals. The total (combined) number of carbon atoms in R plus R' should be from about 8 to about 22, and is preferably from about 10 to about 16 carbon atoms. It is also preferred that one of R or R' be hydrogen, and still further preferred that R and/or R' be substantially straight chain in character, rather than branched to any considerable extent. R'' in these materials should be an alkyl radical containing at most about 6 carbon atoms, and is preferably an alkyl radical that contains from 1 to 3 carbon atoms. Typical non-limiting examples of some of the vicinal acylamido sulfonate materials that can be advantageously utilized in the practice of this invention include sodium 2-acetamido-n-hexadecane-1-sulfonate, potassium 1-propionamido-n-tetradecane-2-sulfonate, magnesium 2-butylamido-branched dodecane (from α -tetrapropylene)-1-sulfonate, ammonium 6-acetamido-n-hexadecane-7-sulfonate, sodium 2-acrylamido-n-octadecane-1-sulfonate, sodium 2- β -methoxy-propionamido-hexadecane-1-sulfonate, sodium 9-acetamido-n-do-

decane-10-sulfonate, potassium 2-(α - β -dichloropropionamido)-n-hexadecane-1-sulfonate, and the like.

Note that in the compounds represented by Formula 1, above, M can be ammonium, an alkali metal cation (such as Na, K, Li, Rb, Cs, and Fr), or an alkaline earth metal cation (such as Mg, Ca, Ba, Be, Sr, and Ra). Alkali metals, and particularly Na and K are preferred, however.

The beta-ethylenically unsaturated higher alkene sulfonates that are useful in the practice of the present invention are preferably only mono-unsaturated, and have the formula

wherein R''' and R^{IV} are either hydrogen or alkyl radicals. The total (combined) number of carbon atoms in R''' plus R^{IV} should be from about 7 to about 21, and is preferably from about 9 to about 15 carbon atoms. It is also preferred that either R''' or R^{IV} be hydrogen, and still further preferred that R''' and/or R^{IV} be substantially straight chain in character, rather than branched to any significant extent.

These beta-ethylenically unsaturated higher alkene sulfonates can be manufactured by sulfonating at very low temperatures (i.e., $<0^{\circ}\text{C}$.) the corresponding olefin with less than about 1.5 moles of sulfur trioxide per mole of olefin while the olefin is dissolved in a non-reactive solvent; subsequently raising the temperature of the resulting reaction product to above about 20°C ; and then neutralizing the resulting sulfonic acid product. This method yields a mixture of sulfonates, including the desired beta-unsaturated sulfonate, which can be isolated from the reaction product fairly readily by well-known separating and purifying techniques.

It will be understood that generally the olefinic raw materials from which these beta-ethylenically unsaturated sulfonates are made will contain from a trace up to several weight percent or more of di-olefinic materials, depending upon the method of their manufacture. Thus, the sulfonates derived therefrom can contain up to several weight percent of di-functional material without detracting from the benefits that can result from practicing this invention.

Typical, non-limiting examples of the beta-ethylenically unsaturated higher alkene sulfonates that are useful in the successful practice of the present invention include sodium 2-n-hexadecene-1-sulfonate, sodium 2-n-dodecene-1-sulfonate, magnesium 2-n-tetradecene-1-sulfonate, sodium-2-n-octadecene-1-sulfonate, potassium 2-(branched) pentadecene-1-sulfonate, ammonium 2-n-octadecene-1-sulfonate, ammonium 2-n-pentadecene-1-sulfonate, sodium 2-n-dodecene-1-phenyl-1-sulfonate, sodium 2-n-pentadecene-3-sulfonate, potassium 3-n-heptadecene-2-sulfonate, lithium 2-n-octadecene-4-sulfonate, ammonium 1-n-hexadecene-2-sulfonate, calcium 3-n-heptadecene-2-sulfonate, potassium 2-dodecene-1-sulfonate, sodium 1-(branched, from propylene) tridecene-1-sulfonate, sodium 2,9-n-octadecadiene-1-sulfonate, potassium 9-n-octadecene-11-sulfonate, sodium 1-n-octadecene-3-sulfonate, sodium 4-n-hexadecene-3-sulfonate, magnesium 2-n-dodecene-1-sulfonate, ammonium 2-n-dodecene-1-sulfonate, rubidium 2-n-pentadecene-1-sulfonate, sodium 2-n-octadecene-1-sulfonate, sodium 6-n-octadecene-5-sulfonate, sodium 6-phenyl-1-n-pentadecene-3-sulfonate, and the like.

The beta-monohydroxy higher alkane sulfonates that are present in the surfactant compositions of the present invention are those having the formula

wherein R, R' and M have the same meaning in Formula 2 as they do in Formula 1, above. Since the beta-hydroxy higher alkyl sulfonate materials with which this invention is concerned are those which would ordinarily be "by-products" in processes for the manufacture of the vicinal acylamido sulfonates described above, it will be appreciated that the beta-hydroxy sulfonates of the present invention include all of those that can be made from olefins which, in turn, can be used to prepare the vicinal acylamido higher alkyl sulfonates described above. The mixtures of sulfonates of this invention, however, can be made by simply admixing the various, relatively pure individual sulfonates, if desired.

In view of the problems described above, the surfactant compositions of the present invention will ordinarily be prepared by simply physically intermixing the desired amount of beta-ethylenically unsaturated alkene sulfonate with the mixture or blend containing vicinal acylamido alkane sulfonate plus beta-hydroxy alkane sulfonate. Each of these individual surfactants is a solid material under ambient conditions. So, also, are mixtures of the relatively pure materials. Consequently, they can be simply blended together in any conventional mixing or blending equipment designed to handle solid, particulated material. If desired, the surprisingly effective surfactant compositions of this invention can also be manufactured by simply mixing together the individual surfactant materials; either in the dry, solid state, in water to form a slurry or solution that can be dried to yield such "dry," solid compositions, or in water at "end-use" amounts to form immediately useful surfactant solutions.

The mixtures of surfactants of this invention can be shipped, stored and handled in the dry "solid" state if desired. They can be particulated (i.e., powdered, flaked, or granular) and can also be utilized in the form of a solid mass such as a "bar," pellet, or tablet if desired. Compositions containing these mixtures can also advantageously contain any other material that can conventionally be employed in detergent compositions. For example, they can also contain "builders" such as the water-soluble alkali metal phosphates, polyphosphates, sulfates, carbonates, bicarbonates, and the like, all of which "builders" are well-known in the detergent art. They can also contain other compatible surface active materials such as the well-known anionic, nonionic, and amphoteric surfactants, although generally, for best results, when the mixtures of this invention are utilized in conjunction with still other surface active agents, the mixtures of this invention make up at least about 50 and preferably at least about 70 weight percent of the total amount of organic surfactants present in these compositions.

Example I

Into a conventional glass lined reaction vessel fitted with an explosion proof stirring motor and an impeller type stirrer are charged 2000 parts by weight of acetonitrile, 500 parts of chloroform, and 200 parts of 1-n-hexadecene which is a mixture of α -olefins containing from about 12 to about 20 carbon atoms, the average chain length of said olefins being about C₁₆. Over a period of about 1 hour, while the temperature of the resulting mixture is maintained at about -15° C., 100 parts of liquid sulfur trioxide are added to the mixture while violent stirring is maintained. After the addition of the sulfur trioxide, the reaction mixture is stirred for an additional 30 minutes. Then the reaction mixture is warmed under vacuum to about 50° C. to evaporate the excess acetonitrile and chloroform solvents. The product that remains contains about 80 weight percent of 2-dioxy - 3,4 - dihydro - 4 - n - tetradecyl - 6 - methyl-1,2,5-oxathiazine (a so-called "inner anhydride"), a few weight percent of 2-hydroxy-n-hexadecane-1-sulfonic acid, and about 16 weight percent of hexadecane β -sulfonyl.

This residue is then stirred into about 10,000 parts of

hot (ca. 90° C.) water, to which is then added a sufficient amount of a 50 weight percent aqueous solution of sodium hydroxide to neutralize the aqueous solution to a pH of 8. When this neutralized solution is then cooled to about 0° C., crystals settle out of the aqueous mixture and are removed by filtration and subsequently dried to yield a product containing about 80 weight percent of sodium 2-acetamido-1-n-hexadecane sulfonate (i.e., average chain length=C₁₆) and about 20 weight percent of sodium 2-hydroxy-1-n-hexadecane sulfonate (i.e., average chain length=C₁₆). Typical surfactant properties of this type of product are given in the following tables, under the designation of "product from Example I."

15

TABLE I.—EVALUATION AS LIME SOAP DISPERSANT

Sample No.	Sample Tested ¹	Rating
20	Control (soap)	10
1.	"Pure" sodium 2-acetamido-n-hexadecane-1-sulfonate (average C ₁₆)	1-2
2.	"Pure" sodium 2-hydroxy-n-hexadecane-1-sulfonate (average C ₁₆)	8
3.	"Pure" sodium 2-n-hexadecene-1-sulfonate	4
4.	80% sodium 2-acetamido-n-hexadecane-1-sulfonate, 20% sodium 2-hydroxy-n-hexadecane-1-sulfonate (product from Example I)	4-5
5.	50% sodium 2-acetamido-n-hexadecane-1-sulfonate, 50% sodium 2-hydroxy-n-hexadecane-1-sulfonate	6
6.	50% sodium 2-n-hexadecene-1-sulfonate, 50% sodium 2-hydroxy-n-hexadecane-1-sulfonate	7
7.	80% sodium 2-acetamido-n-hexadecane-1-sulfonate, 20% sodium 2-n-hexadecene-1-sulfonate	3
8.	50% sodium 2-acetamido-n-hexadecane-1-sulfonate, 50% sodium 2-n-hexadecene-1-sulfonate	6
9.	66% sodium 2-acetamido-n-hexadecane-1-sulfonate, 17% sodium 2-hydroxy-n-hexadecane-1-sulfonate, 17% sodium 2-n-hexadecene-1-sulfonate	3
10.	85% sodium 2-acetamido-n-hexadecane-1-sulfonate, 10% sodium 2-n-hexadecene-1-sulfonate, 5% sodium 2-hydroxy-n-hexadecane-1-sulfonate	2
40		

¹ Lime soap dispersants tested as a 15 weight percent blend of the dispersant or dispersant mixture with 85 weight percent of sodium coco soap.

45

Sample number 10, above, was prepared by blending into a mixture such as the product from Example I, above, 50 parts of fairly pure sodium 2-n-hexadecene-1-sulfonate (made from a mixture of α -olefins having an average chain length of approximately 16 carbon atoms) equal to the amount of 2-hydroxy material already present in the mixture.

The lime soap dispersant test is one that involves the measurement of the relative stickiness of lime soap scum or curds. Lime soap curds are those that form at the surface of hard water after a soap has been dissolved therein. In addition to distributing the curd through the aqueous system, effective lime soap dispersants decrease or minimize the stickiness of the lime soap curds. In the test, which is conducted at a temperature between 30 and 35° C., 250 parts per million hard water (calculated as CaCO₃) having a Ca:Mg ratio of 2:1 is utilized. Five mls. of a 1 weight percent soap solution (or soap-lime soap dispersant blend) are shaken vigorously in a 50 ml. test tube. Then the resulting foam is immediately stirred slowly into 500 mls. of the hard water in a 600 ml. beaker. After all of the foam is quenched and the solution has stood undisturbed for 2 hours, the amount and particle size of scum, or suspended lime soap curd, are observed and rated in comparison with soap alone and a standard soap-lime soap dispersant composition. Soap gives a low rating of 10, while the standard lime soap dispersed composition is rated 3 in a test such as that just described.

¹ Same samples, according to "Sample No." as in Table I.

The "hand dishwashing test" of Table IV, above, involves the washing by hand of nine-inch dinner plates which are pre-soiled with one teaspoonful each of a synthetic "soil" mixture consisting of 75 weight percent of shortening and 25 weight percent of flour. Washing of the plates is performed (using a dishcloth to remove the synthetic soil) in 4 liters of water having an initial temperature of about 50° C. and containing 0.075 weight percent of the surfactant or surfactant mixture being tested. The number of plates washed (for the data above) is determined by the number of plates which can be cleaned in the normal fashion by the time the lather on the surface of the dishpan has "broken" to the extent that less than half of the surface remains covered with lather. The manipulative procedures of this test are described in greater detail in the Proceedings of the 43rd Annual Meeting of the Chemical Specialties Manufacturers' Association, December, 1956; Procedure No. 3, page 191.

¹ Concentration of surfactant or surfactant mixture in distilled water is 0.125 weight percent.

² Same samples, according to "Sample No." as in Table I.

The foregoing evaluation data illustrate the surprising synergistic action that is exhibited by the surfactant compositions of the present invention. Note that, generally, the surfactant properties of the compositions of this invention are excellent, while in each test, the binary mixture (vicinal acylamido sulfonate plus beta-hydroxy material) is significantly poorer than the compositions of this invention. Similarly, in several of the foregoing tests the compositions of the present invention are significantly better than the relatively pure beta-unsaturated materials.

In order to utilize the non-aqueous surfactant compositions of this invention as general purpose surfactants, they need merely be dissolved in effective amounts, generally at concentrations of at least about 0.005 weight percent or more (up to as much as about 20 weight percent or the limits of their solubility; or even higher if slurries are desired to be used) in water.

Although, in the foregoing example and tests, data for mixtures made from α -n-hexadecene are given, it will be understood that similar comparative data result when data for other mixtures of the present invention are similarly compared.

What is claimed is:

1. A detergent composition comprising a mixture of (a) from about 40 to about 98 weight percent, based on the weight of said mixture, a vicinal acylamido sulfonate having the Formula 1

50 wherein R and R' are selected from the group consisting of alkyl radicals and hydrogen; the total number of carbon atoms in R plus R' being from about 8 and about 22; M is a cation selected from the group consisting of alkali metal, alkaline earth metal, and ammonium cations, and R'' is an alkyl radical containing from 1 to 6 carbon atoms; (b) from about 1 to about 30 weight percent, based on the weight of said mixture, a beta-hydroxy sulfonate having the Formula 2

60 wherein R, R' and M have the same meaning as in said Formula 1; and (c) from about 0.5 to about 30 weight percent, based on the weight of said mixture, of a beta-ethylenically unsaturated sulfonate having the Formula 3

70 wherein M has the same meaning as in said Formula 1, and R and R' are selected from the group consisting of alkyl radicals and hydrogen, the total number of carbon atoms in R+R' from about 7 to about 21.

2. A composition as in claim 1, wherein the amount of said beta-ethylenically unsaturated sulfonate is equal to at least about one half of the amount of said beta-hydroxy sulfonate in said composition.

3. A detergent composition which contains a mixture

wherein R is an alkyl radical containing from about 10 to about 16 carbon atoms, R'' is an alkyl radical containing from 1 to 3 carbon atoms, and M is an alkali metal cation selected from the group consisting of sodium and potassium cations; (b) a beta-hydroxy sulfonate having the Formula 2

wherein R and M are the same as R and M, respectively, in said vicinal acylamido sulfonate; (c) a beta-unsaturated sulfonate having the Formula 3

wherein M has the same meaning as in said Formula 1 and R is an alkyl radical containing from about 9 to about 15 carbon atoms; and the weight ratio of said vicinal acylamido sulfonate to said beta-unsaturated sulfonate, respectively, in said composition being from about 40:1 to about 5:1, and the weight ratio of said vicinal acylamido sulfonate to said beta-hydroxy sulfonate, respectively, in said composition being from about 15:1 to about 4:1.

4. A detergent composition as in claim 3, wherein said R is a straight chain alkyl radical and said M is sodium.

5. A detergent composition as in claim 3, wherein said R is a straight chain alkyl radical and said M is potassium.

6. A detergent composition containing from about 40 to about 98 weight percent of sodium 2-acetamido-hexadecane-1-sulfonate, from about 0.5 to about 30 weight percent of sodium 2-hexadecene-1-sulfonate, and from

about 1 to about 30 weight percent of sodium 2-hydroxy hexadecane-1-sulfonate.

7. An aqueous detergent solution containing from about 0.005 to about 20 weight percent of a synergistically effective surfactant mixture, said mixture containing (a) from about 50 to about 90 weight percent of an alkali metal vicinal acylamido higher alkyl sulfonate compound wherein the acyl group contains from 1 to 4 carbon atoms and the higher alkyl radical contains from about 12 to about 18 carbon atoms and is unsubstituted except for the acylamido and sulfonate groups, (b) from about 5 to about 20 weight percent of an alkali metal beta-ethylenically unsaturated alkene-1-sulfonate, wherein the alkene radical contains from about 12 to about 18 carbon atoms and is unsaturated at only the 2-position, and (c) from about 5 to about 20 weight percent of an alkali metal 2-hydroxy alkyl sulfonate, wherein the alkyl radical contains from about 12 to about 18 carbon atoms.

10 8. An aqueous detergent solution as in claim 7, wherein said higher alkyl, said alkene, and said alkyl radicals are a mixture of straight chain radicals containing from about 10 to about 24 carbon atoms; said mixture having an average chain length of from about 12 to about 18 carbon atoms.

15 9. An aqueous detergent solution as in claim 7, wherein said alkali metal is sodium.
